UNITED STATES PATENT OFFICE

BENJAMIN A. HENDRICKS, OF SEATTLE, WASHINGTON

FUEL OIL HEATER

Application filed September 12, 1927. Serial No. 218,993.

This invention relates to an electric liquid heater and is designed, more especially, for heating fuel oil in connection with an oil burner.

5 The object of the invention, generally is to provide a heater of this character which will be economical in the consumption of electricity and effectual in operation.

A specific object is to provide an electric 10 oil heater wherein an electric heating element is most advantageously employed to utilize a maximum amount of the produced heat to the oil for raising its temperature, and afford a liquid containing heating chamber which is proportioned and arranged 15 with respect to its oil supply and delivery pipe connections that the heating of the oil is performed regularly and efficiently.

The invention consists in the novel construction, adaptation, and combination of 20 parts hereinafter described and claimed.

In the accompanying drawings, Figure 1 is a longitudinal section on line 1—1 of Fig. 2, and Fig. 2 a transverse section on line 25 2—2 of Fig. 1 showing an embodiment of the present invention.

In said drawings, the reference numeral 5 represents a metal tubular oil receptacle to the ends of which are secured heads 6 and 7 30 provided with centrally disposed screw threaded openings within which are engaged oil feed and discharge pipes 8 and 9, respectively, of smaller diameter than said receptacle.

35 Mounted upon the receptacle 5 are two annular plates 10 which extend into the ends of a cylindrical tube 11 and are secured thereto as by means of screws 12. The tube 11 and the end plates 10 constitute the casing of the heater. Within the casing and surrounding the receptacle 5 is an electric heating element comprising a winding of a resistance wire 13 located between two sheets 40 14 and 15 of mica or other suitable electric insulating and refractory material. 16 represents leading-in wires for said resistance wire and which desirably are protected from injury by the provision of a pipe conduit 17 therefor which is secured to one of the casing ends as shown in Fig. 1. The space sur-

rounding the outer sheet or wrapping 15 of mica, within said casing is filled with a suitable heat insulating material 18 such as asbestos.

In use, the heater is used in a horizontal 55 position, and for an oil burner of known construction is included in the fuel supply line 8—9 in close proximity to the furnace in which the burner is installed. The operation of the heating element with respect to the oil within the receptacle is obvious, but the arrangement of the element with respect to a receptacle which is relatively of large diameter compared with the fuel feed and delivery pipe and its horizontal 60 arrangement differs from other heaters which have come to my notice. The purpose of the large diameter of the receptacle affords capacity for a large volume of oil in the receptacle and which volume is heated from 65 its periphery inwardly toward the longitudinal axis of the oil body. The relatively cold oil is supplied centrally into one end of such oil volume and not against the relatively hot surface of the receptacle; 70 while the delivery of oil centrally from the other end of such volume ensures an equable 75 temperature of fuel to a burner. Such an arrangement of a drum, as it were, in the pipe line 8—9 tends to ensure uniformity as to temperature and fluidity of the oil which is delivered from my heater, resulting in a practically constant and even nozzle flame when associated with an oil burner.

What I claim, is,—

1. An electric oil heater consisting of a horizontally disposed cylindrical casing having its opposite ends centrally apertured, a cylindrical oil receptacle of uniform diameter throughout its length extending 80 through the apertures of the respective ends, said receptacle being of a length exceeding that of the casing to project exteriorly of both ends, oil supply and discharge pipes of less diameter than the receptacle connected 85 to respective extremities and axially of the same, tubular members comprising sheets of electric insulating material disposed concentrically about the outer periphery of the receptacle and in spaced relations, one with 90

another, an electric heating device comprising a coil of resistance wire provided in the space between said tubular members, and a mass of insulating material surrounding the outer of said tubular members, said oil receptacle being unobstructed to permit a free circulation to the oil passing therethrough.

- 5 2. An electric oil heater consisting of a horizontally disposed cylindrical casing having its opposite ends centrically apertured, a cylindrical oil receptacle of uniform diameter throughout its length extending through the apertures of the respective ends, said receptacle being of a length exceeding that of the casing to project exteriorly of both ends, oil supply and discharge pipes of less diameter than the receptacle connected to respective extremities and axially of the same, an electric heating device comprising a coil of resistance wire provided exteriorly of said receptacle, and a mass of insulating material surrounding said resistance wire, said oil receptacle being unobstructed to permit a free circulation to the oil passing therethrough.
- 10 20 25

Signed at Seattle, Washington, this 18th day of August, 1927.

BENJAMIN A. HENDRICKS.
